UNITED STATES PATENT OFFICE.

EMANUEL W. DUNN, OF SAN FRANCISCO, CALIFORNIA.

HEATER.

1,113,966.

Specification of Letters Patent. Patented Oct. 20, 1914.

Application filed October 6, 1913. Serial No. 793,725.

To all whom it may concern:

Be it known that I, EMANUEL W. DUNN, a citizen of the United States, residing at San Francisco, in the county of San Francisco, State of California, have invented new and useful Improvements in Heaters, of which the following is a specification.

This invention relates to orchard heaters, and relates particularly to a heater and system of heating in which a fuel reservoir is used to supply one or more heaters distributed through an orchard.

It is the object of my invention to provide, first, an efficient heater where all of the fuel will be consumed and wherein combustion will take place as efficiently as possible, and second, to supply an efficient and simple means for supplying the fuel to the individual heaters.

My system includes a reservoir with suitable piping or other means for supplying liquid fuel from the reservoir to the heater, and a heater having a body or receptacle into which the fuel is discharged and in which the fuel is burned, the receptacle being capable of holding excess fuel which may be unburned at any instant. The heater itself preferably comprises the receptacle provided with an air inlet and a combustion outlet in the form of a stack. The stack may be provided with auxiliary air inlet means or not, just as desired; but it is preferable to have auxiliary air induction at the bottom of the stack so as to complete the combustion which has been started by the air admitted at the main induction. The major portion of combustion takes place within the body or receptacle of the heater, and final and complete combustion takes place as the gases pass upwardly through the combustion or outlet stack. The heated gases of combustion are delivered directly to atmosphere thereby directly heating the atmosphere in addition to the heat radiated thereinto from the body and stack of the heater.

It is an object in this form of heater to promote complete combustion within the heater at the generator; oil and air being fed in proper proportions.

I have illustrated a preferred form of my invention in the accompanying drawings, in which,

Figure 1 shows a vertical section of the heater and its connection with the fuel reservoir, Fig. 2 shows a plan view of the

heater, Fig. 3 shows a vertical section of a modified form of heater, Fig. 4 shows a heater and a variant form of fuel feeder, Fig. 5 shows a heater in variant form. 60

In the drawings the numeral 10 may designate the body or receptacle of a heater, being in any preferred form. Preferably, in my present design the body is oblong rather than square or circular, although any suitable configuration may be used. In this form of heater, I place the air induction means 11 at one end of the body and the outlet stack 12 at the other end of the body. The air induction means 11 may consist in 70 a down draft tube 13 with or without apertures 14 through which the air passes into the interior of the body or receptacle 10; and the passage of air through the tube may be controlled by a suitable damper arrangement 15 of any desired form.

In the form shown in Figs. 1, 2 and 3 I prefer to lead the liquid fuel through a pipe 20 from a reservoir 21, controlled by a valve or other means 22, into the down draft tube 13 somewhat in the manner shown in the drawing. The fuel is admitted to the heater in quantities depending upon the amount of combustion and the quantity of heat desired, the fuel dripping from the pipe 20 down 85 through the tube 13 as illustrated, into a cup 41. The air drawn through the tube 13 comes into immediate contact with the fuel in the cup and carries vapor therefrom into the immediately surrounding flame. 90 Combustion takes place in the receptacle 10 around the cup 41; and this combustion heats the oil in the cup and the entire receptacle and causes the immediate vaporization of the fuel which drips from the 95 pipe 20 into the cup. The cup is always hot, by reason of the flame playing around it; and the fuel is vaporized by the heat of the cup. The cup, or any other flame exposed part, may be made of or lined with fire 100 resisting material, such as fire clay. The heated gases of combustion rise to the outlet stack 12 and are delivered directly to the atmosphere. Auxiliary air for combustion of the gases may be fed into stack 12 in 105 various manners; or may be fed into the body 10. In Fig. 1 I have shown the stack 12 with a series of perforations 30 through which the air is drawn from the surrounding atmosphere to mingle with gases of combustion to cause their complete and perfect burning. In Fig. 3 I have shown the stack

110

12 provided with means for feeding auxiliary air for combustion beneath its lower edge to mingle with the heated gases as they pass upwardly through the stack. In this 5 form I use a conical collar 35 provided with perforations 36 above the lower edge of the stack. The stack is supported by resting within and upon the collar 35; and an annular space is left between the collar and 10 stack into which air may pass through the perforations 36. Air passes inwardly and downwardly under the lower edge of the stack and then upwardly to mingle with the 15 gases of combustion during their passage through the stack. In this manner I provide for full and perfect combustion of the fuel, delivering to the atmosphere nothing but clear gases without any smoke.

In Fig. 4 I have also shown an inlet 50 20 for air to the body 10; by this means complete combustion may take place within the body and the body be highly heated to radiate heat in great quantities to the surrounding atmosphere. In the form shown in Fig. 25 4 I illustrate a heater essentially the same as that shown in Fig. 3; but I show a variant form of fuel feeding means. In the form of Fig. 4 I introduce the fuel so that it is presented within the body 10 at a point 30 directly beneath the air induction tube 13, so that the downwardly moving draft of air will pass directly over the fuel as it is fed from the pipe 40. I may provide a small cup 41 in which fuel will stand exposed to 35 the downward draft of air. The pipe 40 leads to a suitable fuel reservoir 43 which is entirely closed. The regulation of the supply of oil to the burner is effected by an arrangement somewhat as illustrated. The 40 pipe 40 has a vertical branch 42 which is open to the atmosphere at its upper end; and the arrangement is such that when the fuel has been fed out of the reservoir to an extent sufficient to produce a partial vacuum 45 therein and to retard the feeding of the oil, the air pressure on the open end of pipe 42 will force the oil level therein continually lower until a small quantity of air will pass from the pipe 42 through the pipe 40 back 50 to the reservoir 43, relieving the vacuum and allowing more fuel to flow. In this manner the flow of fuel is more or less controlled by the rapidity with which the fuel is consumed in the heater.

In Fig. 5 I have shown a form of heater 55 in which air is introduced from below and deflected by a cap 60 to pass over the fuel surface. Fuel may drip from pipe 62 onto the cap 60. I may introduce water with my oil fuel as illustrated in Fig. 1, through pipe 20^a controlled by valve 20^b. The water is immediately converted to super-heated steam; and this steam has the property of 60 cleaning away all asphalt or other deposit.

As I have stated hereinbefore, any num- 65

ber of heaters may be fed from a single reservoir for fuel; and this arrangement has several advantages. In the first place, the heater may be made relatively small and inexpensively, sufficient cubic capacity being required only for combustion of the fuel. And another particular advantage resides in the simplicity of operation of the heater. Instead of filling each individual heater with fuel, it is only necessary to fill a single reservoir for a great number of heaters, thereby greatly reducing the labor required of keeping the heaters always in condition for emergency operation.

I claim—

1. An orchard heater, comprising a combustion receptacle, an air inlet tube for the receptacle, a combustion outlet stack for the receptacle, auxiliary air inlet means admitting air to the stack, and means to feed fuel into the air inlet tube and into the draft of air drawn through the air inlet tube into the receptacle. 80

2. An orchard heater, comprising a combustion receptacle, an air inlet tube for the receptacle, a combustion outlet stack for the receptacle, auxiliary air inlet means admitting air under the lower edge of the stack, and means to feed fuel into the air inlet tube and into the draft of air drawn through the air inlet tube into the receptacle. 85

3. An orchard heater, comprising a combustion receptacle, an air inlet tube extending into the receptacle, a combustion outlet stack for the receptacle, auxiliary air inlet means admitting air under the lower edge of the stack, and means to feed liquid fuel into the air inlet tube. 90

4. An orchard heater, comprising a combustion receptacle, a perforated air inlet tube extending into the receptacle, a damper at the outer end of the tube to control the inlet of air thereto, a combustion outlet stack on the receptacle, means to admit air under the lower edge of the stack to its peripheral portions, and means for feeding liquid fuel into the perforated inlet tube to be carried by the air draft into the receptacle. 105

5. An orchard heater, comprising a combustion receptacle, an air inlet tube extending downwardly into the receptacle open to atmosphere at its upper end and open to the receptacle interior at its lower end and having perforations in its walls inside the receptacle, a combustion outlet for the receptacle, means for feeding auxiliary air into the combustion outlet, and means for feeding fuel into the tube above the perforations therein into the draft of air drawn through the inlet tube. 115

6. An orchard heater, comprising a combustion receptacle, an air inlet tube extending into the receptacle and open to atmosphere at its outer end and having perfora- 120

130

tions in its walls inside the receptacle, means to control admission of air to the tube, a combustion outlet stack on the receptacle, means for feeding auxiliary air into the combustion outlet, and means for feeding fuel into the tube above the perforations therein into the draft of air drawn through the inlet tube.

In witness that I claim the foregoing I have hereunto subscribed my name this 9th 10 day of September 1913.

EMANUEL W. DUNN.
